MINIATURE PARLOR GOLF GAME APPARATUS
OR SIMILAR ARTICLE

David Powell, Michigan City, Ind.

Application September 9, 1954, Serial No. 32,218

Term of patent 7 years

(Cl. D34—5)

Fig. 1 is a top plan view of a miniature parlor golf game apparatus or similar article, showing my new design;

Fig. 2 is a side elevation looking toward the left at Fig. 1, viewed from the line 2—2; and

Fig. 3 is an end elevation looking upwardly toward Fig. 1, viewed from the line 3—3.

The broken line fragmentary showing of a supporting platform is for illustrative purposes only.

I claim:

The ornamental design for a miniature parlor golf game apparatus or similar article, substantially as shown and described.
